UNITED STATES PATENT OFFICE

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE

LOCOMOTIVE STOKER

Application filed July 18, 1927. Serial No. 206,701.

The invention relates to locomotive stokers of the type wherein conveyors carry the fuel from the tender and raise it to a suitable elevation for scattering over the grates, and has for its principal objects to simplify the structure, to reduce the number of parts, and to provide a light, small organization that can be readily applied to locomotives both new and old and will meet the requirements 10 of locomotive service.

Further objects and advantages of the invention will appear from the description read in connection with the accompanying drawings, in which

15 Fig. 1 is an elevation of a portion of the backhead with the stoker applied thereto, the lower portion of the elevator conduit being shown in vertical section and the transfer conveyor being shown in transverse vertical 20 section on a plane rearwardly of the universal joint;

Figs. 2, 3 and 4 are sectional views taken on the lines 2—2 of Fig. 1, 3—3 of Fig. 4 and 4—4 of Fig. 1 respectively;

25 Fig. 5 is a substantially horizontal section corresponding to Fig. 4, and showing an alternative construction;

Fig. 6 is a substantially vertical section taken on the line 6—6 of Fig. 5; and

30 Fig. 7 is a detail, partly in elevation and partly in section, of a structure appearing in Fig. 3.

The backhead of the locomotive, generally indicated by 10 in Fig. 1, is made up of the 35 back sheet 11 (Figs. 2 and 3), the front sheet 12, and the mud ring 13. As indicated in Fig. 2, this backhead frequently inclines forwardly and upwardly.

The grates are generally indicated at 14, 40 and the firing opening is shown at 15 as being formed by flanges 16 and 17 of the sheets 11 and 12 overlapped and secured together at 18. One side wall of the cab is indicated at 19 in Fig. 2 and a deck is shown in that 45 figure at 20.

The stoker, generally speaking, is composed of a transfer conveyor A which serves to bring the fuel from the tender substantially 50 along the center line and then carry it forwardly and laterally through an extension

B on the locomotive to an upwardly directed elevator conveyor C, which delivers the fuel to a swinging chute D and which chute in turn delivers the fuel onto a firing plate E from whence it is blown over the grates by a 55 steam blast issuing from the box F.

The transfer conveyor, or what may be termed the tender unit, may be of any particular form desired and is here illustrated as comprising a casing 21 within which is rotatably mounted a screw 22. In the preferred 60 form this conveyor lies along the center line of the locomotive and tender, and reaches the locomotive below the deck 20.

The elevator C includes an extension 24 on the intermediate conduit B which forms its base, a central section 25, and a removable curved portion 26, which latter may include the spout 27 from which coal is delivered to the chute D. The straight portion of the elevator C is set off at one side of and is parallel with the vertical center line of the locomotive. It also extends upwardly along the backhead and is substantially parallel 70 with it so as to occupy the minimum amount of space in the cab.

Within this straight portion there is mounted an elevating screw 28, the lower end of which has a shaft 29 extending therefrom and upon which a bevel gear 30 is secured. Another gear 31, suitably mounted in the gear 80 casing 32, meshes with the gear 30, and motion is imparted to the gears for driving the elevator through the universal joint 33 by 75 any desirable means.

The central section 25 and the curved portion 26 of the elevator are held in place by bolts 34 and studs 35 in order that they may be readily removable when it is desired to 85 dismount the elevator screw.

The box 36 substantially rectangular in form and open at its front side, forms the upper portion of the stoker casing, and is provided at its rear side with an opening 37 corresponding to the firing opening 15, and adapted to be closed by the conventional or 90 any preferred form of fire door.

The chute D is mounted upon the shaft 38, journaled in the box 36 near its upper left 95 hand corner portion 39. By oscillating the 100

shaft 38, the chute D may be made to swing back and forth and thereby play the stream of coal across the distributing plate E and hence cause it to be scattered in a waving shower over the grates. This oscillation may be accomplished in a variety of ways. As shown, the arm 40, loosely mounted on the shaft 38, is connected with a link 41 operated by a bell crank 42 which, in turn, is operated by a rod 43 connected to a crank 44, driven by a gear 45 mounted in the casing 32 and meshing with the gear 30.

Integral with the arm 40 is a notched segment 46 adapted to receive a latch 47 carried by an arm 48 fitted to the shaft 38. The latch 47 has two arms 49 and 50, the latter cooperating with the segment 46 and the former co-operating with the fixed segment 51, or a notch on the side of the box 36.

By this means the chute may be connected with the rocking mechanism to swing back and forth and direct the stream of coal on the grate, or it may be set in a selected position to direct the stream of coal to one side or the other, or the intermediate portion of the fire box, or it may be set as indicated in dotted lines in Fig. 1, entirely above the firing opening and out of the way of the fireman in hand firing.

The left side of the chute D is provided with an upward extension D' which will receive the coal from the spout 27 when the chute is in a position to deliver coal to the right portion of the distributing plate.

The spout 27 may be in one piece with the section 26 of the elevator casing, or it may be welded to the wall of the box 36.

The extension transfer conduit B is preferably a casting and forms the base of what may be termed the locomotive unit. On its forward side (Fig. 3), it is secured to a bracket 53 which, in turn, is secured to the backhead, or other suitable part of the locomotive.

At its rear side the base B has an opening to receive fuel from the tender unit A, to which it is connected by a suitable universal joint, generally indicated by 23.

One wall 54 (Fig. 4) of the unit B is substantially straight in vertical section, and extends forwardly and laterally from the right side of the tender unit curving sufficiently gently to facilitate the passage of the fuel and then curves rearwardly into the semi-cylindrical portion 55 and then returns to the left side of the transfer conveyor.

The semi-cylindrical portion 55 forms the lower left side of the elevator casing. The transfer screw 22 terminates a sufficient distance from the wall 54 to prevent compacting the fuel against that wall. The pressure of the screw, however, moves the fuel forwardly and laterally through the intermediate conduit and delivers it directly against the elevating screw 28 at which time the fuel is mov-

ing substantially at right angles to the direction in which it is to be elevated. Thus, the fuel reaches the elevating screw with sufficient pressure to permit the screw to work in the most efficient manner and to prevent the fuel from rotating with the screw and not rising.

The construction here disclosed permits the conveyor A to be located substantially at the center line while the elevator is offset laterally from that line, and yet only a single universal connection will permit the necessary flexibility.

The extension conduit B can generally be located entirely below the deck of the locomotive and hence will not intrude upon the limited space in the cab. This conduit, being short and having little or no upward inclination, offers a minimum of resistance to the travel of the fuel, and its presence permits the bend at the upper end of the elevator (where a change of direction of the travel of the fuel presents more difficulty) to be materially reduced.

In the construction illustrated in Figs. 5 and 6, the transfer conveyor A is shortened and the lower end of the elevator is connected to it by an obtuse angled elbow 61, the outer wall of the elbow being preferably vertically curved as shown at 60, to still further facilitate the change of direction of the moving fuel. The elbow is a casting 62 forming the base of the locomotive unit. Preferably the elbow 61 is inclined downwardly toward its delivery end as shown in Fig. 6, thereby facilitating the movement of the fuel.

These two constructions will serve to illustrate the fundamental organization which may be embodied in a variety of other forms and yet preserve the substance of the invention.

Although in both the forms illustrated, the extension of the transfer conduit is shown as being in the base of the locomotive unit, it is, in reality, a part of the transfer mechanism as distinguished from the elevator mechanism.

I claim as my invention:

1. In a stoker for use with a locomotive including a cab, a deck, and a backhead having a firing opening leading into the fire box, and a tender behind the locomotive, the combination of an elevator located adjacent to the backhead and at one side of and parallel with the central longitudinal vertical plane of the locomotive, its lower end being extended laterally and curving backward in a substantially horizontal plane to such central plane, and a transfer conduit carried by the tender and universally jointed to the elevator extension.

2. In a stoker for use with a locomotive, including a backhead having a firing opening leading into the firebox, a tender behind the locomotive, the combination of a transfer conveyor bringing the fuel from the tender to

the locomotive, and located substantially along the center line thereof, a sole elevator conduit spaced laterally at one side of the transfer conveyor for delivering fuel to a point adjacent the firing opening, distributing means receiving fuel from said elevator conduit for delivering it to the fire through said firing opening, an elevator screw in the elevator conduit and a connecting conduit curving laterally in a substantially horizontal plane forming a continuation of, and receiving fuel from, the transfer conveyor and delivering to the adjacent end of said elevator conduit, said transfer conveyor forcing the fuel through said connecting conduit to the elevator screw.

In testimony whereof I affix my signature.
NATHAN M. LOWER.
